United States Patent Office.

C. H. REMINGTON, OF DUBUQUE, IOWA.

Letters Patent No. 69,481, dated October 1, 1867.

IMPROVEMENT IN BULLET MACHINES.

The Schedule referred to in these Letters Patent and making part of the same.

TO ALL WHOM IT MAY CONCERN:

Be it known that I, C. H. REMINGTON, of Dubuque, Dubuque county, Iowa, have invented a new and useful Improvement in Machine for Making Bullets or Shot; and I do hereby declare that the following is a full, clear, and exact description thereof, which will enable others skilled in the art to make and use the same, reference being had to the accompanying drawings, forming part of this specification, in which—

Figure 1 is a sectional side elevation of my improved bullet and shot machine, and

Figure 2 a top view with the pressing dies in section.

Similar letters of reference indicate corresponding parts.

This invention relates to a new and useful improvement in machinery for making bullets or shot by compression or swaging, and consists in a device for feeding rods or wire made of lead or other suitable soft metal in short lengths, cut off successively and pushed into dies which are forced together by slides worked by cams in such manner as to press or swage the lead slug into a round or oval-shaped bullet or shot, as hereinafter more particularly described.

By this machine bullets or shot are rapidly and perfectly formed of any required size or sphericity.

A represents a bench-frame for the support of the machinery, across which, on the top, is hung a shaft, B, operated by a crank fly-wheel, C, or by any suitable power connected therewith. On the shaft B are placed two cams, a a' , which move the slides b b' forward respectively, while they are drawn back by springs q q' under the bed of the machine. Both movements may, however, be effected by the cams. The slide b carries on its forward end a die, c , which is moved to and from a stationary die, c' . In the ends of the dies are formed cup-cavities or recesses that are complements of each other to press a piece of lead into the shape of a bullet or shot, or differently shaped, as desired. The slide b' carries on its forward end a punch, d , that passes through the die c to push a piece of lead up to the end of the die, to be pressed into a bullet. The punch fits in the die exactly, and conforms in its extremity to the shape of the pressing cavity in the die, or has a point on the end to form a cavity in the bullet. The die c has a slot, e , fig. 2, on one side, opening into the hole for the passage of the punch through it, in which slot the piece of lead to be pressed is introduced and forced by a slide, g , which receives its forward movement to push in the lead from a cam-block, h , placed on the side of the fly-wheel C, which acts on it at every revolution of the wheel. The slide is also provided with a spring, h' , to throw it back when the cam has passed, and the die is made adjustable with a set-screw. Attached to the front end of the frame A is a feeding apparatus, consisting of a sliding head-block, k , connected by a clamping-jaw, k^1 , with a sliding arm, k^2 , fastened on the under side of the frame A to a slide piece, k^3 , which is actuated in one direction by a side cam, m , on the fly-wheel C, and is moved back in the other direction by a spring, n .

The operation of the machine is as follows: The lead rod or wire s 's is fed from a reel or any suitable device through the head-block k , between it and the end of the jaw k^1 . The sliding arm k^2 pushes it forward a certain distance, as required, opposite the slide g , through a cutter, i , and as the slide g moves up it cuts off the piece of lead to make a bullet, and pushes it forward into the slot e in front of the punch d , which is then moved forward by the slide b' . The slide b has previously moved the die c up to the die c' , and the punch then forces the lead into the cavity at the end of the dies to form the bullet or shot. The stationary die is provided with a plunger to push the bullet out when it has been pressed or swaged into form, and discharge it through the bed of the machine. The machine may be used for swaging iron or other metals, if desired.

Having thus described my invention, what I claim as new, and desire to secure by Letters Patent, is—

1. The combination of the slides b b' , actuated by the cams a a' , the moving die c , and stationary die c' , the punch d , and the feeding slide g , arranged and operating substantially as and for the purposes herein-described.
2. The head-block k , the clamping-jaw k^1 , the sliding arm k^2 , and slide piece k^3 , actuated by the side cam m , combined and operating substantially as and for the purpose herein described.

C. H. REMINGTON.
